WEB REVERSING UNIT

Adolph M. Zuckerman, New York, N. Y., assignor
to R. Hoe & Co., Inc., New York, N. Y., a cor-
poration of New York

Application February 14, 1936, Serial No. 63,922

12 Claims. (Cl. 101—180)

This invention relates to web-reversing units, and more particularly to web-reversing units to be employed in intaglio or rotogravure web printing machines having a plurality of printing couples.

Heretofore, it has been the practice in the construction and operation of a multi-unit intaglio printing machine to locate the paper roll supports in the line of printing units between selected units, and feed the web in one direction through one or more units to print on one side of the web, and then the web is directed over these units and fed in the opposite direction through the desired number of printing units to thereby print the opposed side of the web. This arrangement has proven unsatisfactory owing to its inflexibility, because it definitely determines the maximum number of colors that can be printed on either side of the web, unless a plurality of paper roll supports are provided along the line of units. Placing paper roll supports in a number of different positions along a line of rotogravure printing units is objectionable, because it obviates the possibility of a compact press arrangement, and, furthermore, it increases the length of the web path. A press room floor space conservation is one of the serious problems now confronting printing machinery engineers and press room executives, and, consequently, any construction which provides a more compact printing machine works to a definite advantage. It is also objectionable to feed the web in one direction through the required number of printing couples or units, and then feed the web in the opposite direction through the selected printing couples or units, because, under such conditions, the units must be made reversible, which greatly increases their cost. In a reversible intaglio rotogravure printing unit, an ink fountain of special design having a doctor blade carrying mechanism at each side thereof is provided, and, owing to the necessity of providing means for the easy and expeditious removal of the printing cylinder from the ink fountain, the additional doctor blade supporting mechanism introduces intricacies in the design that entail considerable expense. Furthermore, when it is necessary to feed the web in both directions through an intaglio web printing unit, with which air drying equipment is employed, it is necessary to provide two driers for each reversible unit, consequently, adding materially to the cost of the machine.

An object of my present invention is to provide a web-reversing unit for multi-units intaglio printing machines, the web-reversing unit being

constructed and arranged, and, also so supported with relation to the line of printing units, that it is movable to any one of a plurality of operative positions along the line of units to reverse the web between selected units, thereby permitting the web to run in both obverse and reverse positions in a common direction through all the units.

An additional object of this invention is the provision of a web-reversing unit, for a multi-unit intaglio web printing machine, having a plurality of cooperable web-engaging components, the web-reversing unit being constructed, arranged and supported, with relation to the line of printing units, to reverse the web between selected printing units without its web-engaging components engaging the printed side of the web.

Another object of this invention is to provide a web-reversing unit for use in a multi-unit intaglio web printing machine having a trackway extending along the printing units, the web-reversing unit being supported by and movable along the trackway and securable in any one of a plurality of operative positions for reversing the web between selected printing units.

A further object of this invention is the provision of an intaglio web printing machine having a plurality of printing couples or units arranged in a line, a trackway extending along and above the printing couples, a web-reversing unit supported by and movable along the trackway and securable in any one of a plurality of operative positions thereon to reverse the web between selected printing couples.

Another object of this invention is the provision of an intaglio web printing machine having a plurality of printing couples arranged in a line, a trackway extending along and above the printing couples, a web-reversing unit having a frame supported by and movable along the trackway, angularly-disposed web-turning bars supported by the frame, a web guide and propeller roller rotatably supported by the frame and operably interposed between the web turning bars, the web-reversing unit being securable in any selected operative position along the trackway to permit the web turning bars and web guide roller to reverse the running web between the selected printing couples, and means for driving the web guide and propeller roller at any selected operative position of the web-reversing unit along the trackway.

It is also an object of this invention to provide an intaglio web printing machine having a web-reversing unit of generally improved construction, whereby the device will be simple, durable,

and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detailed description of an improved multi-color intaglio web printing machine incorporating a novel mobile web-reversing unit will now be given in connection with the accompanying drawings forming a part of the specification, wherein:

20 Figure 1 is a fragmental diagrammatic elevation of an intaglio web printing machine, showing the mobile web-reversing unit applied thereto;

25 Figure 2 is a fragmental plan view depicting the web-reversing unit;

30 Figure 3 is a fragmental end elevation of the improved web-reversing unit, the view being taken in the direction of the arrow indicated in Figure 2;

35 Figure 4 is a fragmental side elevational view of the improved web-reversing unit, the view being taken in the direction indicated by the arrow shown in Figure 2;

40 Figure 5 is a fragmental detailed sectional view, taken on the line 5—5 of Figure 2, depicting the mounting for the web-reversing unit drive gear and web roller supporting shaft; and

45 Figure 6 is a fragmental detailed vertical sectional view taken on the line 6—6 of Figure 4, depicting a supporting roller for mobile web-reversing unit.

50 Referring to the drawings, in which similar reference characters designate corresponding parts, there is depicted a multi-color intaglio web printing machine having a supporting frame 10 arranged to operably support a plurality of web printing units, and each unit includes an intaglio form or printing cylinder 11 and a cooperating impression cylinder or roller 12, which is engaged by a reenforcing or back-up roller 13 of conventional construction. Although the machine supporting structure 10, for sake of brevity, has been referred to as a supporting frame, it is to be understood that the frame may include a separate frame for each printing unit suitably united in conformity with the usual practice, but, 55 inasmuch as this supporting structure forms no part of the invention it has been referred to generally as a frame. Each cylinder 11 is mounted in the usual or conventional intaglio ink fountain 14 to supply impression ink to the running web W. The web W is unwound from a web supply roll R mounted preferably at one end of and supported by the machine frame 10, as shown in Figure 1, and this web is guided from the supply roll R to and through the intaglio 60 printing units or couples by suitable guide rollers 65 of conventional construction.

65 A superstructure frame 16 is mounted upon and is secured to the frame 10 of the intaglio printing machine, and this superstructure frame 70 16 has a rail 17 extending along and above the line of printing units at each side of the machine, and the upper longitudinal edge of each rail 17 is preferably machined to define a trackway 18 to movably support a novel web-reversing unit, to 75 be hereinafter disclosed.

This invention contemplates the provision of a novel web-reversing unit 19 constructed and arranged to move along the tracks 18 of the rails 17 of the superstructure 16 to any selected operative position, where it may be secured to reverse the web between selected printing units. The web-reversing unit 19 includes spaced side members or rails 20, having a spreader or brace 21 secured to each end thereof by bolts or other suitable securing devices 22, and these braces 21 extend transversely across the machine to provide a rigid frame. Pockets or recesses 23 are formed in the lower portion of the side rails 20 to receive rollers or wheels 24 provided to permit the free movement of the web-reversing frame, defined by the side rails 20 and cross braces 21, to slide freely along the trackways 18 of the superstructure rails 17, as will be more fully explained hereinafter. Securing plates 25 are fastened to the side rails 20 at each corner of the web-reversing unit by machine screws or other suitable securing devices 26, as best shown in Figures 4 and 6, and a bearing shaft or spindle 27 extends through suitable apertures, formed in the side rail 20 and each securing plate 25, and also through each roller 24 to rotatably secure the roller 24 within the pockets 22, so that these rollers engage the smooth trackway 18 of the superstructure rail 17 to permit free movement of the web-reversing unit 19 along the trackway. Each securing plate 25 extends downwardly beyond the lower edge of its rail 20 and has an aperture 28 formed therein, as shown in Figure 6, and when the web-reversing unit frame has been moved to a selected operative position along the trackway 18, each aperture 28 aligns with one of a plurality of threaded apertures 30, formed in each rail 17, so that a threaded machine screw or other suitable securing device 31 may be positioned in and extended through the unthreaded apertures 28 and into the threaded aperture 30, as shown in Figure 6, wherein it is secured to securely lock the web-reversing unit frame in selected operative position. A shaft or rod 32 is secured to the rails 20 and extends transversely across the web-reversing unit frame adjacent one end of the frame, and a similar rod 33 is received within apertures 35 formed in the side rails 20, as shown in Figures 2 and 6, to permit longitudinal sliding motion of the shaft 33 within the apertures 35. One end of the shaft 33 is reduced to provide a threaded extension 36, as best shown in Figure 6, and a suitable manipulating nut 37 is threadedly mounted on the reduced extension 36 and is swiveled to a side rail 20 by a suitable plate 38 which is received within an angular groove 40, formed in the outer peripheral portion of the nut 37, the purpose and function of which arrangement will be more fully disclosed hereinafter.

Angularly-disposed turner bars 41 and 42 are provided, and each bar has a sleeve or socket 43 formed at each terminal thereof, and these sockets are mounted on the rods 32 and 33, as best shown in Figures 2 and 6, and secured thereto by screws or other suitable securing device 45. The angular relation of the turner bars 41 and 42 to each other and the web reversing unit frame is determined by the position of the sockets or sleeves 43 on the rods 32 and 33, and a slight adjustment of the angular relation of these turner bars may be effected by rotating the manipulating nut 37, thus causing the bar 33 to move longitudinally within its supporting or bearing aperture 35, to slightly move the terminals of the turner 75

bars, thereby changing their angular relationship.

In order to divert the web from its normal path of travel through the plurality of intaglio printing units, additional guide rollers 15a are suitably supported in predetermined positions with relation to the superstructure rail 17, by any suitable conventional brackets or supports, not shown. The rollers 15a, as will be hereinafter disclosed, 5 guide the web from its normal path of travel into the web-reversing unit 19 in any one of its selected operative positions, so that it may reverse the web W between selected printing units, and the web upon reaching the web-reversing unit is first received by a web-supporting roller 46 mounted for rotation in suitable bearings 47 formed in or mounted on the side rails 20 of the web-reversing unit. These bearings may be plain cylindrical apertures formed in the side rails 20, or, if preferred, conventional anti-friction bearing units may be employed. The web after 10 passing the web-supporting roller 46 is turned upwardly over the angularly-disposed turner bar 41, and then downwardly around a roller 48 rotatably mounted in bearings 50 formed in or supported by brackets 51 which are secured to a side rail 20 of the web-reversing unit 19, as indicated at 49, and best shown in Figure 2. Then the web 15 is guided inwardly around a propeller roller 52, 20 mounted in anti-friction bearings 53, supported in the bracket 50, as shown in Figure 5. In order to drive the propeller roller 52, a gear 55 is secured to one terminal of the shaft 54 of the roller 52, by a key or other suitable securing device 51, and the gear 55 meshes with any one of a plurality of drive gears 56 that are carried by a shaft 57 extending longitudinally along the superstructure frame 16, and this shaft is rotatably mounted in suitable bearing brackets 58 25 secured to the rail 17 of the frame, as indicated at 60. Each gear 56 is secured at a predetermined position along the shaft 57, so that it will mesh with the gear 55 in a selected position or station, and such station is chosen to permit 30 the web-reversing unit to reverse the web between selected printing units. After the web turns inwardly around the propeller roller 52, it is turned upwardly around the angularly disposed bar 42, and moves longitudinally in a direction away 35 from the web supply roll R and through a slot 61 formed in an end brace 21 of the web reversing unit, and then downwardly around a roller 62 rotatably mounted in bearings 63 formed in or supported by the side rails 20 of the web-reversing unit, and next over one of the extra 40 web guide rollers 15a back into the normal web path. A shaft 65 is positioned to parallel the roller 48, and, it is mounted for turning movement in bearings 66 formed in the outer terminals 45 of the brackets 51. Spaced arms 67 are secured to the shaft 65, and each arm 67 has a roller 68 rotatably mounted at its outer terminal to cooperate with the propeller roller 52 in feeding the web through the web-reversing unit. One 50 end of the shaft 65 has a manipulating arm 70 secured thereto, and this arm may be moved to and secured in any selected position in order to adjust the rollers 68 in correct operating relationship to the roller 52, an operation which is well known and understood by those skilled in the 55 art.

In operation, if it is desired to feed the web W from the supply roll R directly through the intaglio printing units A, B, C, and D, this may be accomplished by simply guiding the web along

the conventional guide rollers 15 and through the selected printing couples where the web is engaged by the form cylinders 11 and impression cylinders 12, thereby printing on one side thereof. However, if it is desired to reverse the web 5 W between any selected printing units, it is simply diverted from its normal path of travel, defined by the guide rollers 15, and led over the guide rollers 15a, as shown in full line at the left of Figure 1, through the web-reversing unit 10 19, then over an additional guide roller 15a back into its normal path of travel. In the arrangement depicted in full line in Figure 1, the web W passes through the printing couple A to receive a single impression on one side thereof, and it is 15 next guided through the web reversing unit 19 where it is reversed, and then down around a web guide roller 15a back into the normal web path, and finally it is led through the printing units B, C and D to receive three additional 20 colors on the opposed side of the web. By employing the arrangement depicted in dotted lines in Figure 1, the web W is directed through its normal path of travel over the rollers 15 and through the printing units A, B and C. It is 25 next diverted from its normal path of travel over the guide rollers 15a, through the web reversing unit 19 and then guided back into its normal path of travel where an impression is made on the opposite side of the web by the printing 30 unit D. It is manifest that by employing applicant's arrangement, the web may be reversed between any selected units, so that any desired number of impressions may be made on each 35 side of the web, and the web supplied from a single web supply roll station positioned at one end of the line of units without reversing the direction of rotation of the printing components of the units. This works a definite advantage, because a single web drying device M may be 40 positioned adjacent the single normal web path of travel, whereas, in arrangements heretofore employed, in which the web ran in two directions through a common printing unit, it was necessary to employ two air drying devices for a single printing unit. Furthermore, applicant by providing means for reversing the web above and between adjacent printing units makes it possible to position the web supply roll at one end of the machine, thus avoiding a plurality of 45 50 web stations and consequent space loss and expense. An additional advantage is gained in providing means for leading the web in both obverse and reverse relation in a common direction through all the printing units, because then 55 a simplified fountain and doctor blade arrangement may be employed, thereby effecting substantial economy in equipment cost.

It is to be understood that the present embodiment of my invention may be considered in all respects as illustrative and not restrictive, and it will be further understood that each and every novel feature and combination present in or possessed by the mechanism herein disclosed forms a part of the invention included in this 65 application.

I claim:

1. In a web printing machine, a plurality of printing couples, a web-reversing unit movable to and securable in any one of a plurality of 70 operative positions relative to the printing couples for reversing the web between the impressions of selected printing couples, and means for guiding the web to and through the printing couples and web-reversing unit.

2. In a web printing machine, a plurality of printing couples, a trackway extending along and above the printing couples, a web-reversing unit supported by and movable along the trackway 5 to any desired operative position for reversing the web between the impressions of selected printing couples, and means for guiding the web to and through the printing couples and web-reversing unit.
- 10 3. In a web printing machine, a plurality of printing couples, a trackway extending along and above the printing couples, a web-reversing unit supported on and movable along the trackway to any desired operative position to reverse the web 15 between the impressions of selected printing couples, means for securing the web-reversing unit in any desired operative position along the trackway, and means for guiding the web to and through the printing couples and web-reversing unit.
- 20 4. In a web printing machine, a plurality of printing couples, a trackway extending along and above the printing couples, a web-reversing unit supported by and movable along the trackway 25 to any one of a plurality of predetermined operative positions to receive and reverse the web between the impressions of selected printing couples, means for securing the web-reversing unit in a selected operative position along the trackway, 30 and means for guiding the web to and through the printing couples and web-reversing unit.
- 35 5. A web-reversing unit, for a web printing machine having a plurality of printing couples and a trackway extending along and above the printing couples, including a frame movable along the trackway to any selected position thereon, means for securing the frame in any selected position along the trackway, angularly-disposed bars supported by the frame, a guide roller rotatably supported by the frame and operably interposed between the said bars, the said bars and guide roller cooperating to reverse the running web between the impressions of selected printing couples.
- 40 6. A web-reversing unit, for a web printing machine having a plurality of printing couples and a trackway extending along and above the printing couples, including a frame movable along the trackway to any selected position thereon, means 45 for securing the frame in any selected position along the trackway, angularly-disposed bars supported by the frame, a driven web guide roller rotatably supported by the frame and operably interposed between the said bars, the said bars and guide roller cooperating to reverse the running web between the impressions of selected printing couples.
- 50 7. In a web printing machine, a plurality of printing couples, each couple printing on one side of the web, a trackway extending along and above the printing couples, a web-reversing unit, having a plurality of web-engaging components, supported by and movable along the trackway to any one of a plurality of operative positions to reverse the web between the impressions of selected printing couples, the said web-engaging components engaging only the unprinted side of the web, and means for guiding the web to and through the printing couples and web-reversing unit.
- 55 8. A web-reversing unit, for an intaglio web printing machine having a plurality of printing couples and a trackway extending along and above the couples, including a frame movable along the trackway to any selected position thereon, means for securing the frame in a selected position on the trackway, angularly-disposed bars supported by the frame, a guide roller operably interposed between the bars, the bars and guide roller cooperating to reverse the web between the impressions of selected printing couples and arranged to engage only the unprinted side thereof.
- 60 9. In an intaglio web printing machine, a plurality of printing couples, a web-reversing unit having a frame, means for securing the web-reversing unit in any one of a plurality of operative positions between selected printing couples, angularly-disposed bars supported by the frame, a guide roller rotatably supported by the frame and operably interposed between the said bars, the said bars and guide roller cooperating to reverse the web between the impressions of selected printing couples and arranged to engage only the unprinted side thereof.
- 65 10. In an intaglio web printing machine, a plurality of printing couples, a trackway extending along and above the couples, a web-reversing unit having a frame movable along the trackway, means for securing the web-reversing unit in any one of a plurality of predetermined operative positions along the trackway, angularly-disposed bars supported by the frame, a guide roller rotatably supported by the frame, means for driving the guide roller at any one of the said predetermined operative positions of the web-reversing unit, the said bars and guide roller cooperating to reverse the running web between the impressions of selected printing couples.
- 70 11. In an intaglio web printing machine, a plurality of printing couples, a trackway extending along and above the couples, a web-reversing unit having a frame movable along the trackway to any one of a plurality of operative positions of the said unit, means for securing the web-reversing unit in any one of the said operative positions, angularly-disposed bars supported by the frame, a guide roller rotatably supported by the frame, a drive shaft extending along the printing couples, and means for operably connecting the drive shaft to the guide roller at any one of the plurality of operative positions of the web-reversing unit, the said bars and driven guide roller cooperating to reverse the running web between the impressions of selected printing couples.
- 75 12. In an intaglio web printing machine, a plurality of printing couples, a trackway extending along and above the couples, a web-reversing unit having a frame movable along the trackway to any one of a plurality of operative positions of the said unit, means for securing the web-reversing unit in any one of its operative positions, angularly-disposed bars supported by the frame, a guide roller rotatably supported by the frame, a gear secured to the guide roller, a drive shaft extending along the printing couples and driven by a power component of the printing machine, a drive gear secured to the drive shaft at any one of the said operative positions of the web-reversing unit to mesh with the said guide roller gear, the said bars and driven guide roller cooperating to reverse the running web between the impressions of selected printing couples.

ADOLPH M. ZUCKERMAN.
